WILLIAM FRIEDMAN, OF NEW YORK, N. Y., ASSIGNOR TO LUPE, INC., OF NEW YORK,
N. Y., A CORPORATION OF NEW YORK

CONTAINER

Application filed November 17, 1927. Serial No. 233,784.

This invention relates to containers, and more particularly to containers such as carried by women and are commonly termed "vanity boxes" for holding a make-up material, such as face powder.

The objects of the invention are to provide an improved container of this sort which is adapted to use with "loose powder" as distinguished from a "powder compact"; to enable the powder to be securely retained against inadvertent spilling or loss; to provide for very easy application of some of the powder to a powder puff; to secure immediate closure of the container upon removal of the powder puff or the like; to thus obtain a container for loose powder having means for readily dispensing the powder similar to the operation of obtaining powder from the present day compact; to enable the container to be used either in this manner like a compact or as the usual loose powder containers are now used; to provide a container which may be repeatedly refilled; to secure simplicity of construction and operation; and to obtain other advantages and results as may be brought out in the following description.

Referring to the accompanying drawing in which like numerals of reference indicate similar parts throughout the several views:

Figure 1 is a plan of a "loose powder" container constructed in accordance with my invention;

Figure 2 is a sectional view thereof on line 2—2;

Figure 3 is a similar sectional view showing the dispensing retainer raised, as for filling the container;

Figure 4 is a similar sectional view showing the mode of operation in applying powder to a puff;

Figure 5 is an exaggerated view of a central portion of the dispensing retainer; and

Figures 6, 7 and 8 are exaggerated views

of several forms of cross-sectional constructions of retainer segments.

In the specific embodiment of the invention illustrated in said drawing, the reference numeral 1 indicates the body or box portion of a "vanity" or container, this box or body portion being adapted to receive a make-up material in powder form. It has been common practice heretofore to provide a pair of covers for such a box, one covering the other when closed and the outer one having a reflecting surface. Room enough is left between the covers for receiving and carrying a powder puff and sometimes other articles. When such a construction is used, the outer cover is opened, the powder puff removed, and then the other or inner cover is opened and the powder puff dipped into the powder. There is accordingly danger of the powder spilling or blowing, excessive amounts of powder are used, and the devices have proved so unsatisfactory that women have shown a marked preference for the powder compacts, that is, powder in cake form.

In the present invention, I provide an outer cover 2, and, closing the usual opening 3 of the box but adapted to be enclosed also by said outer cover 2, is an inner cover which I prefer to call a dispensing retainer 4. Both the cover and the retainer are preferably hinged, as at 5 and 6 respectively, to the body, so they may be opened independently of each other, and have suitable snap fastening means as usual for retaining them releasably closed. The dispensing retainer 4 is intended to be opened only for filling the box 1.

The dispensing retainer 4, forming an essential part of the present invention, is of such nature that it is normally closed to prevent escape or spilling of the powder in the box 1. It is constructed, however, so as to automatically provide for escape of a limited amount of powder when a powder puff or the like is rubbed over the same. The openings 90

through which the powder thus escapes, nevertheless, will close as soon as pressure is removed. Of the various ways for accomplishing this action, I have illustrated herein 5 a retainer which is stamped or cut, between a continuous rim 7 and an integral centerpiece 8, into one or more spiral segments 9. The material is preferably sufficiently resilient to normally retain the segments in the plane of 10 the outer margin or rim 7 and the centerpiece 8 so the retainer will provide a substantially smooth surface under normal conditions. However, the spiral cutting of the retainer enables the segments to be depressed out of 15 said plane and create a crevice between the segments, at which time powder may escape through the several crevices. Accordingly, when a powder puff or the like 10 is wiped across the retainer, with some pressure, powder will be obtained on the said powder puff, but immediately upon removal of the pressure, the retainer will close and prevent escape of unnecessary amounts of powder.

It is to be understood that the cross-sectional configuration of the segments 9 is not confined to the shape or proportions herein illustrated, the necessity for clearness causing the exaggeration of dimensions and distortion of proportions. Furthermore, the segments 30 are not necessarily stamped out of the same piece of material as the rim and centerpiece, but may obviously be otherwise constructed or attached. Preferably the segments are two or more spirals as clearly indicated in Figures 1 and 5 for obtaining better support of the centerpiece and greater assurance of a perfect closure under normal conditions. If desired, the closure between the segments may be insured with greater certainty by sloping the abutting edges one way 40 or another. In Figure 7 I have illustrated segments 11 in cross-section having side edges sloping with respect to the top and bottom of the segments, while in Figure 8 I have shown the segments 45 12 as round in cross-section, enabling the same to be constructed of wire if so desired.

It will be observed that while the device is designed and intended for securing the 50 powder therefrom by pressure upon the retainer, it is so constructed that the retainer may be swung open and the powder obtained directly from the box if so desired. Accordingly the device may be used any other way 55 as best suits the desires of the user. It may be added, that in actual use of the device, pressure on the retainer causing the same to sink into the box causes a pressure within the box resulting in the ejection of powder. 60 Even when the powder is getting low in the box, the pressure of the powder puff on the retainer causes air within the box to seek escape which is through the crevices between the segments and with this escape of air a 65 quantity of powder will be carried along also.

Obviously other detail changes and modifications may be made in the construction and use of my improved "vanity" or container, and I do not wish to be understood as limiting myself to the precise construction illustrated 70 or mode of operation indicated, except as set forth in the following claims when construed in the light of the prior art.

Having thus described my invention, I 75 claim:

1. A container for powdered substances having a dispensing retainer, said retainer having a plurality of depressible resilient segments, the depression of which provides 80 crevices therebetween substantially in the direction of depression for dispensing the powdered substances within the container.

2. A container for powdered substances providing a dispensing retainer having a centerpiece and a rim, and a plurality of spiral segments arranged close together side by side so as to normally form a closure and connected to the rim and centerpiece for supporting said centerpiece from the rim.

3. A container for powdered substances having a dispensing retainer, said retainer providing a substantially flat portion so as to be readily wiped with a powder puff, there being a plurality of slits in said substantially flat portion of the retainer, said slits being so arranged as to permit depression of said retainer to create openings in said retainer to permit the escape of a limited amount of powder therethrough.

4. A container for powdered substances, comprising a closure for said container having a substantially flat surface readily wiped with a powder puff, said closure having resilient portions adapted to be depressed and permit passage of a powdered substance to 105 the outside of the closure.

5. A container for powdered substances, comprising a closure for said container having a substantially flat surface readily wiped with a powder puff, said closure having resilient portions adapted to be depressed and permit passage of a powdered substance to the outside of the closure said resiliency of the portions of the closure normally retaining the said portions in the plane of the closure.

6. A container for powdered substances having a dispensing retainer, said retainer providing a plurality of spirals substantially in a plane so as to be readily wiped with a powder puff.

7. A container for powdered substances, comprising a closure for said container having a relatively extensive surface accessible to be readily wiped with a powder puff, said closure having alternate resilient portions 125 and cuts therein, portions of each cut being out of alignment so as to enable the resilient portion of the closure to be depressed.

8. A container for loose powder having a closure, said closure having a pliable powder

dispensing surface comprising alternate resilient portions and crevices from which powder may be obtained by manipulation of a puff against said surface.

- 5 9. A container for powdered substances, comprising a closure having a relatively extensive surface accessible to be readily wiped with a powder puff, said closure having a plurality of portions cooperating with each
10 other adapted to be depressed and permit passage of a powdered substance to the outside of the closure.

WILLIAM FRIEDMAN.
